UNITED STATES PATENT OFFICE

JOHN MARKMAN, OF FORRESTON, ILLINOIS

DRAINAGE PUMP

Application filed December 28, 1928. Serial No. 329,019.

My invention relates particularly to drainage pumps such as are employed for conveying the water from low land and discharging the same into a river or the like,—it being understood however that the pump is capable 5 of other uses too numerous to mention.

The invention has for its primary object to provide a very simple and efficient device of the class described which will move great 10 volumes of fluid or semi-fluid with a minimum expenditure of power,—the nature of the construction being such as to render it capable of being readily assembled and disassembled.

The invention also resides in certain novel 15 features of construction, combination and arrangement of the various parts all of which will be fully set forth in the accompanying description, or will readily suggest themselves to those skilled in the art upon reference to the accompanying drawings forming a part of this specification.

While the preferred embodiment of the invention has been illustrated in the drawings, yet it will be understood that the same is susceptible of considerable change and modification 20 within the spirit and scope of the subject matter claimed hereinafter.

In the drawings, wherein the same reference 25 characters have been used to designate the same parts in all views,

Figure 1 is a vertical sectional view through a dike or the like and showing, combined therewith, a pump installation incorporating my invention;

Figure 2 is a cross sectional view taken on the line 2—2 of Figure 2;

Figure 3 is a section on the line 3—3 of Figure 1;

Figure 4 is an enlarged detailed sectional view showing the joint connection between the pump unit and the tank or housing;

Figure 5 is a group perspective view of the wall and tank assembling guide portions.

Referring specifically to the drawings, numeral 1 denotes a dike or wall of cement located at the river bank and which wall will, of course, have footing considerably below the river bed. The wall may be interposed at

where it is desired that lowland water be emptied into the river.

The wall 1 has an opening 2 which is preferably located well below the surface of the river and adjacent low land so that all the drainage water from the lowland may drain 55 to the opening 2 in the wall.

The wall opening 2 is provided with a cylindrical casing 3, which is suitably sealed in said opening. The casing 3 projects through the wall 1 into the river and has its projecting end cut on a bias, as shown, to provide a valve seat 3^a for the flap valve 4, which is hinged to the casing 3, as indicated at 4^a. The valve 4 will, of course, be open when the pump is in operation to discharge fluid into the river past the valve. The valve 4 is controlled by a rod 5 leading to the top 60 of the wall 1 and which is pivoted to the valve, as indicated at 5^a.

The other end of the casing 2 is suitably flanged, as at 2^a, for connection as at 2^b to the flange B' of a valve casing B which extends 65 through a hole 6^a in tank 6.

The tank 6 is preferably cylindrical in form and is of a height to extend substantially to the top of the dike. The bottom of the tank 6 is embedded in the ground at a depth approximately equal to the depth of the footing of the cement wall 1. In any event, the tank must be low enough so that the water from the lowermost drainage ditch of the drainage area will drain thereinto as will be described more specifically later on.

The wall 1 is provided with one or more vertically disposed guide-ways 7, which comprise opposed, off-set flanges of heavy iron bolted to the wall 1, as indicated at 8. The tank 6 is provided with a number of headed rib or stud members 9, which are adapted to slide in the guide, which is to say under and between the guide-flanges, as clearly shown in the drawings. Thus, the tank may be dropped into the excavation from above,—the studs 9 engaging in the guide-way 7 serving to hold the tank assembled against the wall 1.

The pumping unit is removably carried by the tank and its construction and mode of 100

assembly in the tank will now be specifically referred to.

The pumping unit comprises, generally, a casing 10 which is made up of two sections 11, 12, which are bolted together as indicated at 13, the bolts extending through flanges 11^a, 12^a of the respective sections. It will be understood from the drawings that the casing 10 is halved—so as to speak,—in the direction of its length. The casing sections 11, 12 define respectively, the upper and lower halves of the cylindrical water conduit 14 and motor chamber 14'. The sections 11, 12 at the inlet end of said conduit 14 have beveled flanges 11^b, so that the same can be bolted to the flange 15^a of the cylindrical valve casing 15, which extends through the inlet hole of the tank and has its outwardly projecting end cut on a bias, as indicated, to provide a valve seat 17 for a flap valve 18 which is pivoted, as at 19, to said valve casing. It will be understood that the valve casing 15 extends into a well or a hole located at the lowermost point of the drainage area. Thus, all the water will flow into the valve casing 15 and then into the passage 14 when the valve 18 is open. The valve 18 is controlled by a rod 20 which can be operated from the top of the tank 6. The passage 14 is off-set, as shown, and is separated from the motor chamber 14' which is closed except for a rear end closure plate 10^a.

The flanges 11^a, 12^a terminate short of the end of the casing 10 adjacent the gate valve casing B. At this end the casing 10 is circular and contains only conduit 14. To effect a connection between the main casing 10 and gate valve casing B, I provide a collar C having lateral inturned circumferential flange C' at the inner end and an outwardly and rearwardly flared circumferential flange C'' at its other end. Flange C' bears against the circumferential end of casing 10 beyond the ends of side flanges 11^a, 12^a of the sections 11, 12 which form casing 10. This end of casing 10 has a lateral flange formed by the semi-circular end flanges D of sections 11, 12. Between flanges D, C' is a compressible gasket E. Flange C'' of collar C fits into the mating flange B'' of gate valve casing B and the two are secured together by bolts F. Obviously gasket E seals the joint between C and 10, and since C slides on 10 the latter with C can be removed from tank 6 without disturbing the attachment of gate valve casing B to flap valve casing 2. As shown, the two sections 11, 12 of main casing 10 are bolted together on a line parallel with the axis of the impeller shaft 22 which extends into the off-set discharge end of the passage 14 and carries the impeller 23 disposed therein. The packing gland 24 through which shaft 22 extends, is halved, one-half being carried by the section 11 and

the other half by the section 12. Within the compartment 14' is a thrust bearing, the fixed portion of which is defined by the sections 11^c, 12^c of the respective casing sections. The shaft 22 is provided with a number of spaced shoulders 40 suitably engaging with the partitions 41 of the thrust bearing sections so as to take up the end thrust of the shaft 22 induced by the flow of water through the passage 14, (see Figure 1).

Of course, the rear end of the motor compartment 14' will be closed, as shown. The impeller shaft 22 extends through the thrust bearing housing 11^c, 12^c and has connection with the armature shaft 25 of the motor 26 through the flexible coupling 27 which may be of any preferred or conventional design.

It is desired to point out at this stage of the description that the gate valve casing B, previously mentioned, has a gate valve 28 which is operated by a control handle 29, as indicated. This gate valve 28 will be closed when the pump is being repaired.

The top of the tank 6 is provided with a doorway 30 and also with windows 31. Within the tank 6 there is a spiral stairway 32, which is accessible from the doorway 30. The stairway leads to the bottom of the tank and gives ready access to the pump unit for purposes of inspection, installation or repair.

The top or closure 33 of the tank may be bolted to a supporting flange 36, as at 35. Also the closure 33 may have a central ring 37 for attachment of hoisting tackle for raising or lowering the tank.

Having thus described my invention, what I claim as new and desire to secure by Letters Patent is:

1. In a device of the class described, a wall, a tank, and guide means associated with the wall and tank whereby the latter can be slid into place and maintained in close proximity to the wall, and a pump unit in said tank having an inlet through one side thereof and an outlet through the other, the wall having an opening adapted to register with said pump outlet of the tank.

2. A device of the class described comprising a dam, a pump unit, said dam having a hole through which fluid may be discharged by said pump unit, and a guiding connection between said pump unit and dam, for holding the two assembled and whereby the pump unit can be slid vertically to and from operative position.

3. The combination with a dam, of a casing, a guiding connection between said casing and dam whereby the latter can be guidingly slid into operative position, said casing and dam having openings adapted to register the one with the other for the discharge of fluid therethrough, a pump unit within said casing and comprising a housing having a conduit, impelling means located in said conduit for discharging matter through said casing

opening and dam opening, said conduit having a fluid inlet through the casing wall, and valved means for closing the outlet of fluid.

5. In a device of the class described, a pump unit comprising a housing having a fluid inlet passage therein, said passage being off-set adjacent its discharge and, an impeller in the off-set end of said passage, a
10 shaft upon which said impeller is journalled and extending through the off-set wall of said housing passage, said housing having a chamber into which said shaft extends, said housing comprising two sections united on a line
15 parallel with the axis of said shaft, and a thrust bearing in part formed by said shaft and in part formed by the respective sections of said housing, a motor in the aforementioned chamber and a flexible connection between said motor and said shaft adjacent
20 said thrust bearing.

5. In a device of the class described, a pump unit comprising a housing having a fluid passage therein, said passage being off-
25 set immediate its end to provide two relatively off-set legs, an impeller disposed in one of the legs of said passage, a shaft upon which said impeller is mounted, said shaft extending through the bend or off-set wall of
30 said passage, said housing comprising two sections united on a line parallel with the axis of said shaft, said sections defining a packing gland for said shaft, shoulders on said shaft, a thrust bearing formed in part
35 by each of said sections and engaging said shoulders of the shaft, a motor having a flexible connection with said shaft for driving the same, and a housing formed in part by each of said housing sections or enclosing
40 the motor and thrust bearings.

In testimony whereof I affix my signature.
JOHN MARKMAN.
